ASBESTOS FIBERS IN MINE ROOF COATINGS
 William C. Streib, North Plainfield, N.J., and James G. Rowe III, Houston, Tex., assignors to Johns-Manville Corporation, New York, N.Y., a corporation of New York

No Drawing. Filed Oct. 11, 1957, Ser. No. 689,479
 9 Claims. (Cl. 169—2)

This invention relates to the use of asbestos floats or fibers and mixtures of these with limestone for mine roof coatings. Although disclosed in connection with asbestos fibers, other mineral fibers such as fibrous talc, anthophyllite, rock wool, wollastonite and other asbestosiform materials may be used.

During the initial cutting of a mine it is necessary to provide the mine roof and walls with a coating of rock dust to diminish the danger of explosion and to increase visibility. In this invention, asbestos floats or fibers are used to coat the mine roof and walls so that the asbestos may adulterate the coal dust below the explosion point. As used in the specification and claims, the term, asbestos fibers, is meant to include both asbestos fibers and asbestos floats.

Also, it has been customary in some localities to cover mine roofs with asphalt and other materials to reduce spalling, cracking and rock fall. The coated roofs are then dusted with ground or particulate limestone or other types of ground rock to help set the coating, to lessen the fire hazard, and to improve visibility. Considerable difficulty has been encountered with these processes in that: (1) the dust particles have a tendency to become imbedded in and coated by the asphalt; (2) the dust particles allow the asphalt to drip through, thus forming protrusions from the mine roofs which allow moisture to concentrate in certain areas and to result in annoying drippings; and, (3) the dust particles do not readily adhere to the coating and require repeated application. This invention solves these problems by using asbestos floats or fibers for coating the mine roof. The asbestos fiber, either alone or mixed with ground or particulate limestone, is applied to the asphalt coating and the walls by spraying.

It is a primary object of this invention to provide a method for coating mine roofs and walls which reduces the danger of explosion and increases visibility.

The invention will be more fully understood and further objects and advantages thereof will become apparent when reference is made to the following detailed description of a preferred embodiment of the invention.

As a coal mine is evacuated, it is necessary to continually coat the mine roof and walls so as to adulterate the coal dust below the explosion point and to increase the visibility of the surroundings. In locations where the geographical formation and the condition of the mine is favorable, asbestos floats or fibers alone are used to provide the desired coating. In this process, mixes of 100% asbestos floats or fibers are sprayed in the usual manner so that the asbestos adheres to the mine roof and walls. After application, the asbestos remains in a flaky condition so as to adulterate the coal dust below the explosion point by the gradual dissipation of the asbestos from the roof and walls as the result of air turbulence.

Where the geographical formation and the condition of the mine is not ideal, the mine roof is coated with asphalt to reduce spalling, cracking and rock fall. To lessen the fire hazard, to set the coating and to improve the visibility, the asphalt coating is then sprayed with dry mixes of 100% asbestos floats or fibers. The asbestos adheres to the asphalt coating with such consistency that only one application is necessary whereas previously two and three coats of limestone dust were required.

2

Also, the asbestos reduces the drippings of the asphalt through the dust layer which had previously resulted in many undesirable protrusions from the mine roof. The color life of the coating is high since the asbestos floats or fibers do not have a tendency to become embedded in and coated by the asphalt.

Under some conditions, it may be desirable for economic reasons to spray a mixture of asbestos fibers and limestone dust onto a mine roof and walls as the coating. As with the asbestos floats and fibers alone, this may be applied to a mine roof with or without the asphalt coating. Unusual and advantageous results have been obtained with a mixture of 25% asbestos fibers and 75% particulate limestone by volume. A mixture in the above proportion is prepared and sprayed on the mine roof and walls with customary spraying apparatus. The addition of the asbestos reduces the dust in the atmosphere during spraying and also removes the necessity of applying a second coat.

The use of asbestos fibers or floats either alone or in mixtures with ground or particulate limestone has produced coatings for mine roofs and walls which are far superior to prior coatings. The asbestos fibers or floats remain in the applied condition so that after many months of application the asbestos is more readily dislodged than other coatings which have a tendency to cake. This is highly advantageous since the coal dust prevailing in the mine is adulterated below the explosion point by the gradual dissipation of the coating from the walls and roof into the atmosphere as the result of air turbulence. Thus, since the asbestos retains its original condition, it can provide this highly desired result for a much longer time.

Having thus described the invention in rather full detail, it will be understood that these details need not be strictly adhered to and that various changes and modifications may suggest themselves to one skilled in the art, all falling within the scope of the invention as described by the subjoined claims.

What we claim is:

1. The method of treating a mine roof and walls to adulterate the coal dust below the explosion point and to afford proper illumination which comprises coating the mine roof and walls with a layer of asbestos fibers.
2. The method of treating a mine roof and walls to adulterate the prevailing coal dust below the explosion point and to afford proper illumination which comprises spraying a mixture of 100% asbestos fibers on said roof and said walls.
3. The method of treating a mine roof and walls to adulterate the prevailing coal dust below the explosion point and to afford proper illumination which comprises coating the mine roof with asphalt to reduce spalling, cracking and rock fall, and coating said mine roof and said walls with a mixture of 100% asbestos fibers.
4. The method of treating a mine roof and walls to adulterate the prevailing coal dust below the explosion point and to afford proper illumination which comprises coating the mine roof with asphalt to reduce spalling, cracking and rock fall, and spraying said mine roof and said walls with a mixture of 100% asbestos fibers.
5. The method of treating a mine roof and walls to adulterate the prevailing coal dust below the explosion point and to afford proper illumination which comprises coating the mine roof with asphalt to reduce spalling, cracking and rock fall, and coating said mine roof and said walls with a mixture of asbestos fibers and particulate limestone, said mixture comprising at least about 25% by volume of asbestos fibers.
6. The method of treating a mine roof and walls to adulterate the prevailing coal dust below the explosion point and to afford proper illumination which comprises

coating the mine roof with asphalt to reduce spalling, cracking and rock fall, and spraying a mixture of asbestos fibers and particulate limestone on said asphalt coating and said walls, said mixture comprising at least about 25% by volume of asbestos fibers.

7. The method of treating a mine roof and walls to adulterate the coal dust below the explosion point and to afford proper illumination which comprises coating the mine roof and walls with a material comprising inorganic mineral fibers in the amount of at least about 25% by volume.

8. The method of treating a mine roof and walls to adulterate the coal dust below the explosion point and

to afford proper illumination which comprises coating the mine roof and walls with inorganic mineral fibers.

9. The method of treating a mine roof and walls to adulterate the coal dust below the explosion point and to afford proper illumination which comprises coating the mine roof and walls with a mixture comprising inorganic mineral fibers and particulate limestone, said mixture comprising at least about 25% by volume of inorganic mineral fibers.
